(57) **CLAIM**

The ornamental designs for a soap dispenser bracket, as shown and described.

DESCRIPTION

FIG. 1 is a front elevational view of a soap dispenser bracket showing our design;

FIG. 2 is a rear elevational view thereof;

FIG. 3 is a left side elevational view thereof, a right side elevational view being a mirror image of the left side elevational view;

FIG. 4 is a top plan view thereof;

FIG. 5 is a bottom plan view thereof;

FIG. 6 is a top perspective view thereof; and,

FIG. 7 is a bottom perspective view thereof.

1 Claim, 7 Drawing Sheets
